United States Patent Office

Des. 205,685
Patented Sept. 6, 1966

205,685

BOX

Wesley W. Simpson, New York, N.Y., assignor to Adele Simpson Inc., New York, N.Y., a corporation of New York

Filed July 16, 1965, Ser. No. 86,244

Term of patent 3½ years

(Cl. D58—12.6)

FIG. 1

FIG. 1 is a front, left side and top perspective view of a box embodying my novel design; and

FIG. 2 is a rear, left side and bottom perspective view thereof, the right side being a mirror image of the left side.

I claim:

The ornamental design for a box, as shown and described.
